DESIGN FOR A GAME BOARD

George H. Bradley and Merrill K. Cragun, Minneapolis, and William J. Madden, Jr., Pine Beach, Minn., assignors to Paul Bunyan, Inc., St. Paul, Minn., a corporation of Minnesota

Application October 3, 1938, Serial No. 80,230

Term of patent 14 years

To all whom it may concern:

Be it known that we, George H. Bradley, a citizen of the United States, residing at Minneapolis, in the county of Hennepin and State of Minnesota; Merrill K. Cragun, a citizen of the United States, residing at Minneapolis, in the county of Hennepin and State of Minnesota; and William J. Madden, Jr., a citizen of the United States, residing at Pine Beach, in the county of Cass and State of Minnesota, have invented a new original, and ornamental Design for Game Boards, of which the following is a specification, reference being had to the accompanying drawings, forming part thereof.

Fig. 1 is a plan view, partially broken away, of a game board, showing our new design;

Fig. 2 is an edge view, partially broken away, of the game board; and

Figs. 3, 3a, 3b and 3c are plan views of separate portions of the game board, each of said Figs. 3, 3a, 3b and 3c disclosing a different quarter-section of said game board and all of said figures together disclosing the whole game board.

We claim:

The ornamental design for a game board, as shown.

GEORGE H. BRADLEY.
MERRILL K. CRAGUN.
